UNITED STATES PATENT OFFICE.

WILLIAM H. CALLAGHAN, OF TORONTO, CANADA.

SHOWER-BATH APPARATUS.

SPECIFICATION forming part of Letters Patent No. 603,171, dated April 26, 1898.

Application filed November 4, 1897. Serial No. 657,404. (No model.)

To all whom it may concern:

Be it known that I, WILLIAM HENRY CALLAGHAN, a subject of the Queen of Great Britain, and a resident of the city of Toronto, in the county of York and Province of Ontario, in the Dominion of Canada, have invented certain new and useful Improvements in Shower-Bath Apparatus, of which the following is a specification.

This invention relates to that class of shower-bath apparatus which has for the primary feature a perforated ring adapted to be placed over the head and to rest upon the shoulders of the bather and to have connections with a tap or taps of a bath or other source of water-supply.

The principal objects of my improvements are the effectual distribution of the streams or jets of water over the whole person irrespective of the attitude preserved in the tub and to facilitate adjustment of the different spraying devices, streams, or jets to suit different shapes, forms, or proportions in the body of the bather.

For full comprehension of the invention reference must be had to the accompanying drawings, forming part of this specification, in which—

Figure 1 represents a perspective view of my improved shower-bath apparatus, and Fig. 2 an enlarged detail view of the connections between the annular head or ring and the tap connections.

Similar letters of reference indicate like parts.

A represents a tubular ring or head which when assembled with the other parts preferably forms one integral element. It is provided with a number of perforations *a a* toward its inner and lower sides, through which the water may pass in jets or streams, so as to be distributed over the shoulders and thence to the whole person of the bather. This head or ring may be purely annular or cylindrical or may partake of oval or other desired shape, so long as it may be conveniently passed over the head and rest upon the shoulders of the bather.

B is another perforated pipe extending

downwardly from and rigidly connected to 50 the rear part of the annular head, so as when in use to lie contiguous to the back of the person and to distribute the water over the back and sides, which may be done by arranging the apertures *b b* in series, so as to 55 project the jets or streams at different relative angles. This extension-pipe B is of any suitable length and would have the effect of maintaining the annular head or ring in what may be considered as practically a horizontal 60 plane (at right angles to said pipe connection) and prevent the same from slipping forward, as is the case in the shower-rings now employed and which project the streams of water only over the chest of the bather. 65

At an opposite point upon the head or ring A—that is to say, at that portion which would come in line with the front of the bather's body—I attach another perforated pipe C, preferably of about the same length as the 70 rear pipe B, and arrange said pipe C to be adjustable at any angle which will enable it to adapt itself to the size or formation of the body of the bather, the same being raised to the position shown in dotted lines in Fig. 1 75 previous to placing the annular head or ring A over the bather's head and then pressed or allowed to fall to the position indicated in strong lines in the same figure before turning on the water. 80

I do not claim, broadly, in this application the employment of an annular head or ring.

What I claim, and desire to secure by Letters Patent, is as follows:

1. A shower-bath apparatus comprising 85 water-tap connections, a perforated head or ring adapted to be passed over the head and to rest upon the shoulders of the bather, said head or ring having a perforated pipe in communication also with said water-tap connections, and arranged to adapt itself to the size and form and to distribute the streams of water across the front of the body of the bather, substantially as set forth. 90

2. A shower-bath apparatus comprising 95 flexible water-tap connections, a perforated head or ring adapted to be passed over the head and to rest upon the shoulders of the

bather, a rigid perforated extension from the rear part of said head or ring adapted to maintain same in place and to direct the streams of water toward the back, and an adjustable 5 perforated pipe in direct connection with the water-supply and with the head or ring, and arranged to adapt itself to the size and form

and to distribute the streams of water across the front of the bather's body, all combined and arranged substantially as set forth.

WILLIAM H. CALLAGHAN.
